UNITED STATES PATENT OFFICE.

HARRY W. MANNING, OF PORTLAND, OREGON.

OIL-BURNER.

1,209,603.

Specification of Letters Patent. Patented Dec. 19, 1916.

Application filed April 27, 1916. Serial No. 94,070.

To all whom it may concern:

Be it known that I, HARRY W. MANNING, a citizen of the United States, and a resident of the city of Portland, county of Multnomah, State of Oregon, have invented a new and useful Improvement in Oil-Burners, of which the following is a specification.

My invention relates in general to oil burners adapted for using crude oil, kerosene or distillate as fuel.

The object of my invention is to provide for the efficient heating of the coils through which the liquid fuel passes and thus promote the vaporizing of the fuel oil in a short interval of time.

Another and particular object of my invention is to provide means for preventing the burner becoming flooded with fuel oil because of the accidental extinguishing of the flame while the burner is in action. I attain the latter result by providing in my burner an auxiliary vaporizing chamber provided with the discharge orifice, and providing a check valve at the inlet end of such auxiliary vaporizing chamber, and means for heating the latter; the check valve being so arranged that the pressure of the oil behind the valve will tend to close the same. When my burner is in normal action, a sufficient back pressure of gas will be maintained in the auxiliary vaporizing chamber to keep the check valve open for the passage of fuel gas; but when the auxiliary vaporizing chamber is no longer heated then the check valve will be automatically closed. The details of this and other features of my invention are hereinafter fully described, reference being had to the accompanying drawings, in which:

Figure 1 is a vertical section of my device; and Fig. 2 is a plan view of the base with the auxiliary generator well mounted thereon.

In these drawings, *a* represents the base of the burner, *b* is a circular rib formed thereon, and *c* is a generator well also formed integrally with the base. A circular, segmental auxiliary generator well *d* is mounted on legs *e*, the latter being positioned outside of the rib *b*, which forms a guide for locating the parts in their proper relative positions. The burner-head *f* is shaped like an inverted cup, being provided with a centrally located, downwardly projecting neck *g* and an inclined outer face *h*, the lower edge of which is formed with a

peripheral shoulder *i*. Said burner-head *f* is mounted on legs *j*, which are positioned inside of the rib *b*, the legs being formed integrally with the head. The upper ends of the legs are furthermore provided with outwardly radiating lugs *k*, which form a bearing for a tubular coil *m*.

The neck *g* is made with a central bore, forming the mixing chamber, from which projects a nipple *n*, and a T tube fitting *o* is fixed on the lower end of this nipple. Said fitting is provided with an aperture *p* in axial alignment with the nipple *n*, and lateral air inlet tubes *q* are connected to the lateral legs of the T fitting *o*.

r is an open-ended gauze cylinder, adapted to seat on the shoulder *i* of the burner-head, and *s* is a burner-cap adapted to fit over the burner-head, being supported on the upper edge of the gauze.

The tubular coil *m*, which is concentric with the burner-head *f*, rests on the lugs *k*, and is connected at its inlet end to a fuel supply conduit *t*, the latter being connected with a suitable supply pressure tank, not shown. It is also to be assumed that the supply conduit *t* is provided at some convenient point with a valve by means of which the flow of oil to the burner may be controlled, but as this construction is well known, and forms no part of my invention, it is not detailed herein. The outlet end of the coil *m* is connected to a vertical leg *u*, by means of an elbow *v*. The line of the fuel flow is thence through the elbows *w*, *x*, *y* and the horizontal header *z*. The latter extends radially toward the center of the burner and overlies the well *c*. Mounted on the end of the horizontal header *z* is a valved fuel nozzle *2*, of usual construction, the regulating arm of which is indicated by *3*. The head *4* of this nozzle projects upwardly through the orifice *p* in the T fitting *o*, and the vapors are discharged upwardly through this head in the form of a jet. The lower portion of the nozzle *2* is provided with a removable reservoir cap *5*, adapted to receive any sediment deposited from the oil.

The elbows *w* and *y* connect with a nipple *7* in which is provided a ball check-valve *6*, as shown in Fig. 1. The aperture of the diaphragm in said nipple, controlled by said valve *6*, is larger than the discharge orifice of the nozzle *2*. A pipe *8* extends downwardly from the gas dome *s* and is provided at its lower end with an elbow *9*.

which supports an auxiliary horizontal burner 10, the end of which is closed, and the body of which is perforated so as to emit gas jets for heating said header z . The 5 header z functionates as an auxiliary vaporizing chamber. As shown, the auxiliary burner 10 underlies the auxiliary vaporizing chamber z , but said burner 10 may be otherwise located as convenient.

10 The function of the auxiliary burner is to insure that the auxiliary vaporizing chamber z is kept sufficiently heated at all times to cause the generation therein of a fuel gas at a sufficient rate to effect a back pressure 15 at the check valve orifice which will keep the check valve 6 open against the drag of the fuel gas flowing through said check valve. For otherwise, as apparent, when once the check valve had been seated by the 20 drag of the fluid flowing through it, it would be held shut by the pressure of the fluid behind it. The auxiliary vaporizing chamber z and auxiliary burner 10 also permit my burner to be turned low without danger 25 of going out through insufficient vaporization of the fuel oil.

Should the main burner and the auxiliary burner 10 be accidentally extinguished, then the header z will cool rapidly, decreasing 30 the pressure of vaporized fuel therein to a point where the pressure of oil behind the check valve will close the latter, thus cutting off a further flow of oil through the check valve and preventing the burner from becoming flooded with the fuel oil. When the 35 header z is again heated, the check valve would be automatically released so as to permit the passage of fuel gas. When first starting the burner, the wells c and d have 40 placed in them asbestos waste or other suitable material which is saturated with alcohol, or other inflammable fluid, and ignited; and as soon as the burner has been sufficiently heated the liquid fuel may be turned 45 on gradually and the burner operated in the usual manner. The air drawn in through the lateral inlet tubes q by the injection action will thoroughly mix with the gas in the mixing chamber of the burner cap or gas 50 dome s , the intermixture being emitted through the perforations of the gauze cylinder r . The generator wells for preheating

the oil are located close to the coil m and header z , so as to quickly heat and vaporize the oil. The auxiliary burner 10 also efficiently serves to keep the header z constantly hot, in this wise insuring an efficient head of gas, and the arrangement last referred to also serves to reduce the time required for vaporizing the oil, when first starting up the 60 burner.

The air intake tubes q take air at a point remote from the nozzle 2 and prevent the flames from igniting the jet of gas issuing from the nozzle 2, thus a back-firing to the 65 nozzle is prevented and the efficient operation of my burner is insured.

I claim:

1. In an oil burner of the character mentioned, the combination of an auxiliary vaporizing chamber provided with the burner nozzle at its outlet end, and a check valve controlling the inlet end of such auxiliary vaporizing chamber, said check valve being normally open and adapted to be closed by 70 the drag of the fluid flowing through the same, said auxiliary vaporizing chamber being heated by the burner during the operation of the latter, whereby, in the normal action of the burner, a back pressure of gas 80 is maintained in said auxiliary vaporizing chamber sufficient to resist the closing of the check valve, but permitting the latter to close when the heating of said vaporizing chamber is discontinued. 85

2. In an oil burner of the character mentioned, the combination of an auxiliary vaporizing chamber provided with the burner nozzle at its outlet end, a check valve controlling the inlet end of such auxiliary vaporizing chamber, said check valve being normally open and adapted to be closed by the drag of the fluid flowing through the same, and an auxiliary burner arranged for heating said auxiliary vaporizing chamber 90 and supplied with fuel from the gas chamber of the burner, whereby, in the normal action of the burner, a back pressure of gas is maintained in said auxiliary vaporizing chamber sufficient to resist the closing of the 95 check valve, but permitting the latter to close when the heating of said vaporizing chamber is discontinued. 100

HARRY W. MANNING.
